Primary Examiner — Cynthia R Underwood

(74) Attorney, Agent, or Firm — Drinker Biddle & Reath LLP

(57) **CLAIM**

The ornamental design for a ribbed plate, as shown and described.

DESCRIPTION

FIG. 1 is a top perspective view of a ribbed plate according to the present invention.

FIG. 2 is a bottom perspective view of the ribbed plate of FIG. 1.

FIG. 3 is a top view of the ribbed plate of FIG. 1.

FIG. 4 is a bottom view of the ribbed plate of FIG. 1.

FIG. 5 is a left side view of the ribbed plate of FIG. 1, the right side view, the front view, and the rear view each being a mirror image of the left side view.

FIG. 6 is a cross-sectional view of the ribbed plate of FIG. 1 taken along lines 6-6.

FIG. 7 is a top perspective view of a ribbed plate according to another embodiment of the present invention.

FIG. 8 is a top view of the ribbed plate of FIG. 7; and, FIG. 9 is a cross-sectional view of the ribbed plate of FIG. 7 taken along lines 9-9 in FIG. 8.

The bottom view, left side view, right side view, front view, and rear view of the ribbed plate of FIG. 7 are identical to the bottom view, left side view, right side view, front view, and rear view of the ribbed plate of FIG. 1.
